UNITED STATES PATENT OFFICE

137,947

DESIGN FOR A TOOL FOR APPLYING HOSE CLAMPS OR THE LIKE

Harold H. Beardsley, Denver, Colo., assignor to
Band-It Company, Denver, Colo., a corporation
of Colorado

Application August 10, 1943, Serial No. 110,879

Term of patent 14 years

(Cl. D54—13)

To all whom it may concern:

Be it known that I, Harold H. Beardsley, a citizen of the United States, residing in the city and county of Denver and State of Colorado, have invented a new, original, and ornamental Design for a Tool for Applying Hose Clamps or the like, of which the following is a specification, reference being had to the accompanying drawing, forming a part thereof.

Figure 1 is a plan view of a tool for applying hose clamps or the like showing my new design;

Figure 2 is a plan view of the side opposite to

that shown in Figure 1, showing the element disclosed in full lines in Figure 1; and

Figures 3 and 4 are side elevation views of the element shown in full lines in which the handle or lever is illustrated in different operating positions.

The essential feature of my design resides in the portion shown in full lines.

I claim:

The ornamental design for a tool for applying hose clamps or the like, as shown and described.

HAROLD H. BEARDSLEY.
